(57) **CLAIM**

The ornamental design for a pneumatic tire, as shown and described.

DESCRIPTION

FIG. 1 is a front elevational view of a pneumatic tire showing our new design, it being understood that the tread pattern repeats circumferentially throughout the outer circumference.

FIG. 2 is a front perspective view of one side of the pneumatic tire shown in FIG. 1.

FIG. 3 is a rear elevational view of the pneumatic tire shown in FIG. 1.

FIG. 4 is a side elevational view of one side of the pneumatic tire shown in FIG. 1, it being understood that the other side is of identical appearance; and,

FIG. 5 is an enlarged fragmentary view of FIG. 1.
